UNITED STATES PATENT OFFICE.

HARVEY HUGH DOWNIE, OF SEATTLE, WASHINGTON.

DESIGN FOR A COMBINATION AQUARIUM AND FERNERY STAND.

Application filed December 12, 1928. Serial No. 29,240. Term of patent 7 years.

To all whom it may concern:

Be it known that I, HARVEY HUGH DOWNIE, a citizen of the United States, residing at Seattle, in the county of King and State of Washington, have invented a new, original, and ornamental Design for Combination Aquarium and Fernery Stand, of which the following is a specification, reference being had to the accompanying drawings, forming a part thereof.

Fig. 1 is a front elevation of a fernery embodying my design.

Fig. 2 is an end elevation of the same.

Fig. 3 is a perspective view of said fernery.

I claim:

The ornamental design for a combination aquarium and fernery stand, as shown.

HARVEY HUGH DOWNIE.
